UNITED STATES PATENT OFFICE.

FERRY FRAIZER, OF NEW CASTLE, INDIANA.

DOCUMENT FILE AND RECORD CABINET.

SPECIFICATION forming part of Letters Patent No. 542,189, dated July 2, 1895.

Application filed January 14, 1895. Serial No. 534,877. (No model.)

To all whom it may concern:

Be it known that I, PERRY FRAIZER, a citizen of the United States, residing at New Castle, in the county of Henry and State of Indiana, have invented certain new and useful Improvements in Document File and Record Cabinets, of which the following is a specification.

The invention relates to a document file and record cabinet.

The object is to produce a cabinet of this class of large carrying capacity, and to employ a simple and effective system of indexing and recording, and thereby facilitate filing of documents.

With this object in view the invention consists in an improved construction and certain novel combinations and arrangements of parts, to be hereinafter described and claimed.

In the accompanying drawings, forming part of this specification, similar letters of reference indicate corresponding parts in the several views.

Figure 1 is a view in perspective of one embodiment of the invention. Fig. 2 is a central vertical sectional view of the same. Fig. 3 is a horizontal sectional view of the revolute holder taken between two of the shelves. Fig. 4 is a fragmentary view, in elevation, of the same. Fig. 5 is a view in plan of the record and index sheet.

In the drawings, A represents a stand or table, which is provided with a writing-slide a and a sliding-drawer frame a^2 , in which are mounted two rollers a^3 . At one side the frame of the drawer is recessed to allow for the rotation of the roll-operating cranks a^4 , there being one for each roll.

a^5 designates the record and index sheet, which is arranged so as to be wound from one roll upon the other. In the present embodiment of the invention the sheet is arranged for entries, as shown in Fig. 5. On filing a document under the name of, for example, "Carroll," the sheet is wound from one roller upon the other until that portion bearing at the left-hand margin "C" passes to a point above the support or rest a^6 , which extends across the drawer-frame between the rollers. "a" be-

ing the second letter, the name "Carroll" is written in the first column under the heading "Ca," as shown in the drawings, the initials or given name being preferably written in the second column, after which the document 55 is filed, as will be described later on.

B represents the file-cabinet holder, which consists of a cylindrical or polygonal casing, having one or more doors b , hinged to swing open and expose the interior. The door, if 60 desired, may be provided on its inner side with one or a series of racks for holding pens, pencils, and like articles.

C represents the file-case proper, which consists of a vertical shaft c , stepped in suitable 65 bearings to rotate freely within the casing, and comprises a series of approximately circular shelves c^2 , arranged one above the other, and secured to be rotated with a centrally-disposed shaft. Extending parallel with this 70 shaft and aligned to form compartments c^3 are a series of rods c^4 . These rods are arranged in parallel rows to form four radially-extending diametrically-opposite compartments c^5 between the shelves, the remaining 75 spaces at the corners being each divided into three compartments c^6 by parallel rows of wires c^7 , they being entirely separate and distinct from the compartments c^5 . Strips c^8 serve as sides for the outer compartments c^6 . 80 Thus a file-case of five tiers would contain eighty compartments, and together with its large capacity is at the same time compact and easily handled.

Referring to Fig. 4, wherein the manner of 85 lettering the compartments is illustrated, to file the document under the name of "Carroll," as above referred to, it will be placed in the upper compartment under "Ca," documents under other names being entered and filed in 90 a similar manner.

Having thus fully described my invention, what I claim is—

1. A document file and record cabinet, comprising an indexed record sheet mounted on 95 carrying rollers, the rollers being rotatably held in a suitable movable frame, and a revolute file case consisting in a central shaft having a series of horizontally disposed shelves secured thereto, the space between 100

the shelves being divided into compartments by a series of rods arranged vertically in parallel rows as and for the purpose set forth.

2. A document file and record cabinet, comprising an index record sheet mounted to be wound around rollers, the rollers being rotatably carried by a movable frame arranged to enter a desk-like base, on which is mounted a revoluble file case consisting in a central shaft having a series of horizontally disposed shelves secured thereto, the space between

the shelves being divided into compartments by a series of rods arranged vertically in parallel rows, as and for the purpose set forth.

In testimony whereof I have hereunto affixed my signature in the presence of two subscribing witnesses.

PERRY FRAIZER.
